Primary Examiner — Andrew T Nemeth

(57) **CLAIM**

The ornamental design for a pet feeder, as shown and described.

DESCRIPTION

FIG. 1 is a front perspective view of a pet feeder, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 2 thereof;

FIG. 10 is an enlarged detail view of area 10 in FIG. 2 thereof;

FIG. 11 is an enlarged detail view of area 11 in FIG. 2 thereof; and,

FIG. 12 is an enlarged detail view of area 12 in FIG. 3. The dash-dash broken lines in the drawings illustrate portions of the pet feeder, which form no part of the claimed design.

The dot-dot-dash broken lines in FIGS. 2, 3 and 9-12 illustrate the location and bounds of the enlarged detail views and form no part of the claimed design.

1 Claim, 12 Drawing Sheets
